UNITED STATES PATENT OFFICE.

RICHARD T. CRANE, OF CHICAGO, ILLINOIS.

DESIGN FOR A STATUETTE.

SPECIFICATION forming part of Design No. 17,594, dated August 9, 1887.

Application filed June 9, 1887. Serial No. 240,832. Term of patent 7 years.

To all whom it may concern:

Be it known that I, RICHARD T. CRANE, a citizen of the United States, residing at Chicago, in the the county of Cook and State of Illinois, have invented and produced a new and original Design for Statuettes for Advertising, &c., of which the following is a specification, reference being had to the accompanying drawings, in which—

10 Figure 1 represents what may be called a front elevation of my newly-designed statuette, and Fig. 2 a rear elevation of the same.

The object of my invention is to produce a statuette of bronze or other material, the main 15 feature of which is a crane. This statuette I make in sizes suitable for paper-weights or other like articles. I provide a base, A, of circular form, preferably, though any other shape may be adopted, if desired. Upon this 20 base is a crane, B, in standing position, but with its neck b bent downward, backward, and somewhat to one side, so that the bill b'

will be at the front and reach to the base, as shown in Fig. 1. The crane is also represented as picking up a frog, C, which lies upon the base just under the bill of the crane. On 25 the other side of the crane is the figure of a lily, D, or other like plant, which rises from the base immediately by the side of the crane.

The principal and distinguishing feature of 30 the design is the crane in the position described above.

Having thus described my new design for a statuette, what I claim as new, and desire to 35 secure by Letters Patent, is—

The design for a statuette, consisting of a crane in a standing position, with its neck turned downward and backward, and a base on which the crane stands, substantially as herein shown and described.

RICHARD T. CRANE.
